UNITED STATES PATENT OFFICE.

WILLIAM S. WITTEN, OF CHICAGO, ILLINOIS.

LATCH FOR GATES, ETC.

Application filed October 6, 1919. Serial No. 328,828.

To all whom it may concern:

Be it known that I, WILLIAM S. WITTEN, a citizen of the United States, and a resident of Chicago, in the county of Cook and State 5 of Illinois, have invented certain new and useful Improvements in Latches for Gates, Etc., of which the following is a specification, reference being had to the accompanying drawings.

10 My invention relates to locks and latches for swinging doors or gates, and has for its principal object to provide a simple and inexpensive latch for swinging doors or gates which may be relied upon to operate successfully notwithstanding rough handling or 15 exposure to the weather, and furthermore one which cannot readily be unlatched by animals so that it will be well adapted for use in stockyards or on farm gates. As a 20 further improvement on the underlying structure my invention contemplates the provision of means for locking the latch in operative position so that it cannot be unlocked by unauthorized persons.

25 The manner in which the several objects of my invention are accomplished will be readily understood from the following description thereof in connection with the accompanying drawings, which illustrate the 30 preferred embodiment of my invention. What I regard as new is set forth in the claims.

In the drawings,—

Fig. 1 is a partial side elevation showing 35 the free end portion of a swinging gate having my improved latch mechanism applied thereto, in connection with a gate post which is engaged by the latch to hold the gate in a closed or in an open position, 40 as the case may be;

Fig. 2 is a partial end view of the free end of the gate, illustrating the latch and the locking mechanism for locking it in operative position;

Fig. 3 is a partial horizontal section on line 3—3 of Fig. 2; and

Fig. 4 is a partial vertical section on line 4—4 of Fig. 3.

Referring to the drawings, in which I 50 have shown my invention as embodied in a horizontally-swinging farm gate,—11 indicates the gate, which, in the illustrated arrangement is supposed to swing horizontally. 12 indicates my improved latch 55 which is in the form of an inverted T, as

it comprises an upwardly-projecting shank 13, a latch member or arm 14 which extends laterally from the shank 13 in one direction, and a counterbalancing member or arm 15 which extends from the lower end of the shank 13 in the opposite direction. The upper end of the shank 13 is connected by a pivot 16 with a suitable support attached to the free end portion of the gate, such support being preferably a pair of spaced wooden or metal plates 17 between which the latch is mounted so that it swings freely within a predetermined range. The latch also may be made either of wood or metal as preferred. It will be observed that by this construction the latch forms substantially a pendulum which under the action of the counterbalancing member 15 tends to swing to the left from the position shown in Fig. 1, as said counterbalancing member is made heavier than the latch member 14. To limit the movement of the latch in that direction a stop 18 is provided, preferably in the form of cross-bar connected with the side plates 17. The latch 70 may, however, be swung in the opposite direction to retract the latch member 14 out of operative position, and, I provide for this purpose a cable 19, the lower end of which is connected with the counterbalancing member 15, preferably by a ring 20. 21 indicates a counterbalancing weight carried by the cable 19 for holding the upper portion of the cable under some slight tension and thereby taking up any slack that may exist 80 therein.

As it is sometimes desirable to lock the latch 12 in operative position one of the plates 17 is provided with a boss 22 having a recess 23 therein, in which is mounted a 90 swinging lever or dog 24 mounted by means of a pivot 25 shown in Fig. 4. The portion of said lever at one side of the pivot 25 is adapted to swing into a recess or slot 26 formed at one side of the shank 13, as shown 95 in Figs. 1 and 4, thereby locking the latch 12 against swinging in either direction. Said lever is arranged to be operated to lock or unlock the latch 12 by a rotating cylinder 27 mounted in a suitable bearing 28 fitted in the boss 22, the cylinder 27 being provided with an eccentrically disposed pin 29 which bears against and operates the lever 24, as shown in Fig. 4. The cylinder 27 is 100 preferably a key operated cylinder of the 105 110

plate or pin tumbler type so that it may be rotated only by the insertion of the proper key.

In the construction shown in the drawings the latch member 14 is adapted to project beyond the free end of the gate and to engage a suitable keeper. The particular kind of keeper used is not material except that it should be so constructed as to provide a bevel surface for engagement with the end of the latch member 14 as the gate is moved into latching position, and should be provided with a slot or recess to receive said latch member and hold the gate against swinging. By mounting the latch between side plates as described, said side plates serve to support it against twisting or lateral strains, and also prevent the latch from being forced sidewise out of engagement with the lock lever 24, and protect said lock lever from being tampered with.

My improved latch is peculiarly suitable for use on farm gates or those used on the pens of stockyards as it may be very cheaply constructed, but is nevertheless substantial and reliable. It operates with a minimum of friction; it operates automatically to latch a gate or door in any place around a circle concentric with the gate hinge; it can be opened and closed from any angle or position; it may be used to hold the gate either open or closed; it cannot be opened by animals; it can be securely locked against operation by unauthorized persons; sagging of the gate does not prevent the latch from operating; and it operates with a minimum expenditure of energy since it swings like a pendulum and when released automatically moves to its locking position.

The term gate as used in the specification and claims is intended to comprehend not only gates proper but similar devices such as doors.

What I claim as my invention and desire to secure by Letters Patent, is—

1. A latch comprising side plates spaced apart, a shank pivotally mounted between said side plates and hanging pendulous from its pivot, a rigid member projecting laterally from the lower portion of said shank beyond said side plates, counterbalancing means normally operating to project said member, a cross bar connected with said side plates in position to engage said shank

and limit the extent of projection of said member, a rocking member pivoted to swing transversely of the path of said shank to engage the same and lock it in its operative position, and a key-operated device for actuating said rocking member.

2. A latch comprising side plates spaced apart, an inverted T-shaped member having its shank pivotally connected with said side plates and hanging pendulous from its pivot, said shank having a recess in one side thereof, and a locking device adapted to be moved into said recess to lock said member in operative position.

3. A latch comprising a suitable support, an inverted T-shaped member having its shank pivotally connected with said support and hanging pendulous from its pivot, a rocking member pivoted to swing transversely of the path of said T-shaped member to engage the same and lock it in operative position, and a key operated device for actuating said rocking member.

4. A latch comprising a suitable support, an inverted T-shaped member having its shank pivotally connected with said support and hanging pendulous from its pivot, a rocking member pivoted between its ends to swing transversely of the path of said T-shaped member, one end portion of said rocking member being adapted to engage said T-shaped member to prevent swinging thereof, and a key operated device cooperating with the other end portion of said rocking member for actuating the same.

5. A latch comprising a suitable support, an inverted T-shaped member having its shank pivotally connected with said support and hanging pendulous from its pivot, a rocking member movable into position to lock said T-shaped member in operative position, and a rotary lock cylinder for operating said rocking member.

6. A latch comprising a suitable support, an inverted T-shaped member having its shank pivotally connected with said support and hanging pendulous from its pivot, a rocking member pivoted between its ends, one end portion of said rocking member being adapted to engage said latch to prevent swinging thereof, and a rotary lock cylinder for actuating said rocking member.

WILLIAM S. WITTEŃ.
